UNITED STATES PATENT OFFICE

CHARLES HALL DAVIS, JR., OF ANDERSON, INDIANA, ASSIGNOR TO DELCO-REMY CORPORATION, OF ANDERSON, INDIANA, A CORPORATION OF DELAWARE

IGNITION APPARATUS

Application filed September 14, 1931. Serial No. 562,657.

This invention relates to ignition apparatus for internal combustion engines and more particularly to engines of the reversible type.

It is one of the objects of the invention to control the ignition for forward or reverse operation of the engine as well as to render the ignition inoperative to stop the engine.

Further objects and advantages of the present invention will be apparent from the following description, reference being had to the accompanying drawing wherein a preferred embodiment of one form of the present invention is clearly shown.

15 In the drawing:

The figure of the drawing is a wiring diagram illustrating a form of the invention.

Referring to the drawing, 20 designates a shaft which is driven by the engine at one-half cycle speed, namely, one-half engine speed for a two-cycle engine or one-fourth engine speed for a four-cycle engine. The shaft 20 drives a cam 21 having lobes numbering twice the number of engine cylinders for example, six lobes for a three-cylinder engine. The cam 21 cooperates with rubbing blocks 22 and 32 attached together with leaf spring conductors 23 and 33 respectively, to circuit breaker levers 24 and 34 respectively, carrying contacts 25 and 35 respectively, which cooperate with contacts 26 and 36 respectively, the latter being grounded. The leaf spring conductors 23 and 33 serve to urge the respective circuit breaker levers toward the cam 21, and to conduct current from terminals 27 and 37 respectively. Wires 28 and 38 respectively, connect terminals 27 and 37 respectively, with switch contacts 29 and 39 respectively. Contacts 29 and 39 are engageable by a movable contact 40 pivoted at 41 and connected with ignition coil primary winding 42 connected with battery 43 grounded at 44. A condenser 45 connects switch contact 40 with ground and thereby shunts either 45 pair of interrupter contacts 35, 36 or 25, 26 depending on the position of the switch contact 40.

The ignition coil secondary winding 50 is grounded through the battery 43 and is connected to the central terminal 51 of the dis-

tributor head 52 carrying three equidistant distributor posts 53, each connected with an engine spark plug 54. The central contact 51 is electrically connected with a rotor 55 driven by the shaft 20 and having arms R1 and R2, which operate alternately to distribute sparking impulses to distributor post 53.

Assuming that the cam 21 rotates clockwise when the engine is operating in the direction to propel the vehicle or boat forward, before starting the engine, the operator moves the switch contact 40 into the "forward" position in which it is connected with contact 39, thereby rendering the interrupter, including contacts 35 and 36, operative to control the timing of the ignition for the engine when running in the forward direction. When it is desired to reverse the engine, the switch contact 40 is moved into "off" position to cause the engine to stop and the switch contact 40 is moved into the "reverse" position in which it moves to contact 29, thereby rendering the circuit interrupter having contacts 25 and 26 operative to control the timing of the ignition in the reverse direction. In case the engine has been stopped, it is, of course, necessary to crank the engine in the reverse direction to get it started. However, it is possible to cause the engine to reverse after operating in the forward direction without stopping the engine before reversing takes place. This is accomplished by moving the contact 40 from "forward" position into "off" position to allow the engine to slow down. The lever 40 is then moved into "reverse" position just as one of the pistons is approaching upper dead center, whereupon the engine starts operating in the reverse direction.

Since the condenser 45 is connected with the switch contact 40, it serves either of the circuit interrupters depending on which one is active in the circuit.

By providing two circuit interrupters, one for forward and one for reverse direction of engine operation, the distributor rotor arms R1 and R2 line up properly with the distributor post 53 in either direction of rotation of the distributor shaft 20. It has been the

practice heretofore to employ a single interrupter to control the ignition for a reversible engine. In order to provide for ignition when the engine operates in the reverse direction, the practice has been to shift 5 the circuit interrupter bodily around the cam in order to obtain the correct spark timing for engine reversal. Since the distributor head is mounted upon the support of the interrupter, the distributor posts are bodily moved relative to the distributor rotor. Hence, it was necessary heretofore to provide the rotor arms with unusually wide arcuate projections extending in proximity to 10 the distributor posts in order that the rotor arms could serve to distribute sparking impulses in either direction of rotation of the rotor. Unless the distributor head were made unusually large in diameter, a cross-fire between distributor posts was likely to occur 15 due to the presence of a rotor of unusual width. This objection is overcome in the present invention since it permits the use of a rotor arm of conventional width which eliminates the possibility of cross-fire between the distributor posts.

The means for controlling the amount of spark advance or retard has not been shown as such means is well known to those skilled 20 in this art. It will be understood that when the engine is reversed some adjustment of spark timing may be necessary because whatever setting would give an advanced spark for forward rotation of the engine would give a retarded spark for reverse rotation.

While the form of embodiment of the present invention as herein disclosed, constitutes a preferred form, it is to be understood that other forms might be adopted, all coming 25 within the scope of the claim which follows.

What is claimed is as follows:

Ignition apparatus for a reversible internal combustion engine comprising, in combination, an ignition timer including an interrupter for forward rotation of the engine and an interrupter for reverse rotation of the engine, a single cam for operating the interrupters, a distributor comprising a head and rotor driven with the cam and so located 30 as to distribute properly in conjunction with either interrupter, a coil having a secondary connected with the distributor and having a primary, a current source, and means for selectively connecting the primary with the current source through either interrupter.

In testimony whereof I hereto affix my signature.

CHARLES HALL DAVIS, JR.
